2,496,434

OUTBOARD MOTOR LUBRICATING SYSTEM

Alfred S. Bosma, New Holstein, Wis., assignor to
 Hart-Carter Company, Peoria, Ill., a corpora-
 tion of Delaware

Application October 13, 1944, Serial No. 558,560

6 Claims. (Cl. 184—6)

1

This invention relates to improvements in outboard motors.

Outboard motors as commonly constructed are two cycle and lubricated by mixing a minor quantity of lubricating oil with the gasoline or other fuel in the main fuel tank. This requires the preparation of a special mixture and is otherwise objectionable. It is recognized that greater efficiency and economy in operation can be obtained by the use of a four cycle motor wherein there is a separate oil reservoir and mechanism for feeding said oil to the parts to be lubricated, but oil in a separate reservoir has heretofore presented problems in an outboard motor. One of said problems arises from the fact that an outboard motor is frequently tilted to a horizontal position while on a boat or while being manually carried or placed on its side while being transported in a vehicle. Another problem is that of leakage of oil during operation.

My patent No. 2,458,051, issued January 1, 1949, shows a desirable form of four cycle outboard motor construction having a separate oil reservoir and which is designed to overcome the above-mentioned problems.

It is, therefore, one of the objects of the present invention to provide an improved four cycle outboard motor construction having a separate oil reservoir and oil feeding means, said reservoir being so located and constructed with reference to the position of cooperating parts that the motor may be tilted to all necessary positions or placed on its side without causing oil from the reservoir to enter the cylinder and start trouble, and said reservoir being so located that surplus oil will drain from the bearings back into the reservoir during normal operation.

A further object of the invention is to provide in a construction as above described, improved means preferably including a gear pump for effectively feeding the oil to the parts to be lubricated.

A more specific object of the invention is to provide an outboard motor construction wherein a housing for the vertical drive shaft is so shaped and constructed as to form a reservoir for oil, there being means for delivering oil from the reservoir to the crankcase and for draining surplus oil from the crankcase back into the reservoir. The drain arrangement is so worked out in conjunction with the housing forming the reservoir that the motor may be tilted to a horizontal position while on the boat or while being manually carried, or the motor may be placed on its side or even inverted without permitting oil from the reservoir to enter the crankcase. The arrangement is such that the gear pump, which is

2

employed for forcing the oil upwardly to the crankcase, may be located in a position where it is normally submerged in oil. Thus priming of the gear pump is unnecessary.

5 A further object of the invention is to provide a construction as above described wherein the oil reservoir is so located that the oil therein serves to lubricate the lower bearing for the vertical drive shaft, the bottom bevel gears, and the 10 bearings for the horizontal propeller shaft. It is, therefore, unnecessary with this motor to utilize a special grease for lubricating the bottom gear case.

A further object of the invention is to provide 15 an outboard motor construction, as above described, wherein the oil reservoir is immersed in water during normal use to cool the oil and render operation of the engine more efficient.

A still further object of the invention is to 20 provide an outboard motor construction, as above described, wherein there is a special seal adjacent the propeller which effectively prevents leakage of oil or entrance of water into the bottom propeller shaft housing.

25 With the above and other objects in view, the invention consists of the improved outboard motor, and all its parts and combinations as set forth in the claims, and all equivalents thereof.

In the accompanying drawings, illustrating one 30 complete embodiment of the preferred form of the invention,

Fig. 1 is a vertical longitudinal sectional view through the improved motor;

Fig. 2 is a fragmentary vertical sectional view 35 taken at right angles to Fig. 1;

Fig. 3 is a sectional view taken approximately on the line 3—3 of Fig. 1, on a larger scale, parts being broken away;

Fig. 4 is a sectional view taken on the line 4—4 40 of Fig. 1; and

Fig. 5 is a fragmentary sectional view taken on line 5—5 of Fig. 4.

Referring more particularly to the drawings, the power head is designated generally by the 45 numeral 8 and includes an upper housing portion 9 and a lower housing portion 10. The lower housing portion 10 forms the bottom for the crankcase 5.

There is also a vertical drive shaft housing 50 designated by the numeral 11 which comprises an upper part 12 and a lower part 13.

Bolts 14 secure the bottom housing 10 for the power head in position and also secure the upper part 12 of the vertical drive shaft housing in 55 assembled relationship, there being a bearing plate 15 in between the members 10 and 11.

The vertical drive shaft housing parts 12 and

13 are suitably connected with a horizontal plate or fin 16 therebetween, there being gaskets 17 and 18 at the joint. The fin 16 serves as an anti-cavitation plate.

Within the power head 8 is a four cycle gasoline engine and in the preferred embodiment the engine comprises two cylinders 19 and 20. There may, however, be a greater or a lesser number of cylinders. The cylinder 19 is equipped with two valves 21, one being an intake valve and the other being an exhaust valve, and the cylinder 20 is similarly equipped with two valves 22. The ignition is provided by spark plugs 23 and 24.

Within the cylinders 19 and 20 are pistons 25 and 26 which are suitably connected in the usual manner by connecting rods 27 with the crank-shaft 28. The upper end of the crankshaft projects through a bearing 29 at the top of the head and carries a fly wheel 30. The lower end of the crankshaft is suitably journalled in a ball bearing assembly 31 received in a cup shaped portion of the housing portion 10. Below the ball bearing assembly is an oil seal 32. Suitably splined to the lower end of the crankshaft is a vertical drive shaft 33 which has its upper end portion rotatable in a bearing 34 supported in the bearing plate 15. Below the bearing 34 is an oil seal 35. A starting pulley 36 is suitably associated with the upper end portion of the vertical drive shaft 33.

The lower end of the vertical drive shaft 33 is journalled in a bearing 37, and below the bearing 37 the lower housing portion 13 is formed with a gear chamber 38. In this chamber is a bevel gear 39 rigidly connected to the lower end of the vertical drive shaft 33 and meshing with a bevel gear 40 rigidly connected to a horizontal propeller shaft 41. The inner end of the propeller shaft is journalled in a bearing 42, and an intermediate proportion of said shaft is journalled in a bearing 43 suitably mounted in a boss 44. The boss 44 is connected by bolts 45 with the member 13 to close the gear chamber 38.

On the outer end of the horizontal propeller shaft 41 is the usual propeller 46. Adjacent the inner side of the propeller and surrounding the propeller shaft 41 within the boss 44 is a special seal. This seal comprises a brass disc 47, a cup shaped disc 48 preferably of a phenolic plastic material, and a packing 49 preferably of synthetic rubber. The various members forming the seal are held in effective position by a coil spring 50. This seal effectively prevents escape of oil from the chamber 38, as well as entrance of water to said chamber.

Suitably connected to the lower side of the horizontal fin 16 is a gear pump 51. This gear pump is driven by the vertical drive shaft 33 and is adapted to pump oil from the housing portion 13, through an inlet tube 52, and deliver said oil under pressure upwardly through a tube 53 to the lower end of a bearing 54 for the cam shaft 55. As is clearly shown in Figs. 1 and 2, the bearing 54 is formed in a horizontal partition 56, and said partition has portions which slope toward an outlet opening 56' so that oil which drains from the crank case will be directed into the opening 56' and into a drain tube 57. The drain tube 57 extends downwardly to a point intermediate the length of the drive shaft housing and terminates in an open end 58. When the motor is in normal operating position the open end of the drain tube 58 is well above the normal level 59 of oil in the reservoir.

Oil delivered by the pump 51 through the de-

livery tube 53 enters a duct 60 in the cam shaft and flows upwardly through this duct to lubricate the top bearing 61 for the cam shaft. The majority of the oil from the duct 60, however, is sprayed out of openings 62 in the cam shaft onto the connecting rod bearings.

The cam shaft is provided with a series of cams 63 for operating the intake and exhaust valves 21 and 22. The cam shaft is driven by gears 64 and 10 65, and the former is driven by the crankshaft.

The exhaust conduits from the motor are suitably connected to upper openings 66 of an exhaust tube 67, and the lower end of the exhaust tube is open, as at 68, to discharge below the water level.

A pin 69, which is supported on the exterior of the drive shaft housing 11, extends through a pivot sleeve 70. Connected to the sleeve is the usual clamp 71 for removably securing the motor 20 to a boat. The pin 69 is pivotal within the sleeve 70 to permit steering movement, and the entire motor is swingable on the pin 72 toward a horizontal inoperative position on the boat. In use of the device, the novel housing for the vertical drive shaft forms a reservoir for motor oil. This reservoir must be filled to approximately the level indicated at 59 in Fig. 1. When the motor is in normal operating position, oil in the reservoir will flow downwardly through the openings 73 in 15 the horizontal plate 16 into the reservoir portion 74 of the lower housing part 13 to fill the portion 74. Oil from the reservoir portion 74 will lubricate the bearing 37 and will also pass through one or more holes 75 into the gear chamber 38 to lubricate the bevel gears 39 and 40, as 25 well as the bearings for the propeller shaft 41. The special seal 47 will effectively prevent loss of any oil from the chamber 38 to the exterior.

The motor, of course, operates on gasoline undiluted with motor oil and during operation the gear pump will be operated by the drive shaft 33. This will cause continuous pumping of oil from the lower chamber 74 upwardly through tubes 52 and 53 into the cam shaft duct 60 to lubricate the motor. Surplus oil from the crankcase 7 will continually drain back into the oil reservoir through the opening 56' and drain tube 57.

The vertical drive shaft housing 11 is so shaped 50 and is of such size, and the lower end 58 of the drain tube is so located, that when the motor is swung upwardly on the boat on the pivot 72 to an inoperative position, or when the motor is placed on either side, the oil in the oil reservoir will 55 flow the length of the drive shaft housing portion 11 and the level will always be below the end 58 of the drain tube 57. Thus no oil can flow into the crankcase through the drain tube when the motor is in any one of these horizontally disposed positions.

Even if the motor is completely inverted, the oil in the reservoir will quickly flow to the enlarged upper end portion of the drive shaft housing 11 and the open end 58 of the drain tube 57 will be above the level of the oil while the motor is in inverted position.

With the particular arrangement above described, a four cycle engine may be successfully employed for an outboard motor without any inconvenience resulting from the oil which it is necessary to have in the oil reservoir. The gear pump 51 is advantageously located in a position 70 where it is normally submerged in the oil, and this renders priming unnecessary. Furthermore, the lubrication of the bevel gears and propeller

shaft bearings by the same oil which lubricates the engine itself, renders the use of a separate greasing arrangement at the lower end unnecessary. During use of the motor, the oil in the reservoir is always submerged in the water and is effectively cooled. This cooling of the oil is transmitted to the engine as the oil is used to lubricate the latter. As a result the engine is maintained at a cool running temperature to increase its efficiency of operation.

While the preferred embodiment includes the use of a four cycle engine, the features of the present invention are suitable for use in connection with any engine in which oil is carried in a crankcase. Various other changes, modifications and adaptations may be made without departing from the spirit of the invention, and all of such changes are contemplated as may come within the scope of the claims.

What I claim is:

1. In an outboard motor having a top power head and including a combustion engine having a crankcase in said power head, a bottom for said crankcase, a vertical drive shaft depending from said head and driven by said engine, an elongated vertical housing for said vertical drive shaft connected at its upper end to the power head below the crankcase bottom, a portion of said housing which surrounds the lower part of the vertical drive shaft forming a reservoir for motor oil when the motor is in normal operating position, means for delivering oil from said reservoir to said crankcase, and a return conduit for surplus oil from the crankcase having a discharge end located intermediate the length of the drive shaft housing and above the level of oil therein when the motor is in normal operating position.

2. In an outboard motor having a top power head and including a combustion engine having a crankcase in said power head, a bottom for said crankcase, a vertical drive shaft depending from said head and driven by said engine, an elongated vertical housing for said vertical drive shaft connected at its upper end to the power head below the crankcase bottom, a portion of said housing which surrounds the lower part of the vertical drive shaft forming a reservoir for motor oil when the motor is in normal operating position, means for delivering oil from said reservoir to said crankcase, and a return conduit for surplus oil from the crankcase having a discharge end located intermediate the length of the drive shaft housing and above the level of oil therein when the motor is in normal operating position, the drive shaft housing having a cross sectional area of such size and the discharge end of the return conduit being so located that there is space above the front wall of the housing sufficient to accommodate all oil normally in the crankcase at a level beneath the discharge end of the return conduit when the motor is swung to an inoperative position on a boat.

3. In an outboard motor having a top power head and including a combustion engine having a crankcase in said power head, a bottom for said crankcase, a vertical drive shaft depending from said head and driven by said engine, an elongated vertical housing for said vertical drive shaft connected at its upper end to the power head below the crankcase bottom, a portion of said housing which surrounds the lower part of the vertical drive shaft forming a reservoir for motor oil when the motor is in normal operating position,

means for delivering oil from said reservoir to said crankcase, and a return conduit for surplus oil from the crankcase having a discharge end located intermediate the length of the drive shaft housing and above the level of oil therein when the motor is in normal operating position, there being sufficient space in the upper portion of the drive shaft housing above the discharge end of the return conduit to accommodate all oil normally in the crankcase when the motor is inverted, with said discharge end projecting above the oil level.

4. In an outboard motor having a top power head and including a combustion engine having a crankcase in said power head, a bottom for said crankcase, a vertical drive shaft depending from said head and driven by said engine, an elongated vertical housing for said vertical drive shaft connected at its upper end to the power head below the crankcase bottom, a portion of said housing forming a reservoir for motor oil when the motor is in normal operating position, means for delivering oil from said reservoir to said crankcase, and an elongated return conduit for surplus oil from the crankcase having a discharge end located a substantial distance below the bottom of the crankcase and above the level of oil in the reservoir when the motor is in normal operating position.

5. In a normally vertically disposed outboard motor having a top power head and including a combustion engine having a crankcase in said head, a drive shaft housing below said crankcase forming a reservoir for motor oil and having sidewalls, means for delivering oil from said reservoir to said crankcase for lubricating purposes and an elongated conduit extending into said housing for returning surplus oil from the crankcase to said reservoir, the outlet end of said conduit being located intermediate the length of said drive shaft housing and spaced from the sidewalls thereof.

6. In a normally vertically disposed outboard motor having a top power head and including a combustion engine having a crankcase in said head, a drive shaft housing below said crankcase forming a reservoir for motor oil and having a forward wall portion and a rear wall portion, means for delivering oil from said reservoir to said crankcase for lubricating purposes, and an elongated conduit extending into said housing for returning surplus oil from the crankcase to said reservoir, the outlet end of said conduit being located intermediate the length of the drive shaft housing and positioned closer to the rear wall thereof than to the forward wall.
